(57) **CLAIM**

The ornamental design for an alcohol sensing bracelet, as shown and described.

DESCRIPTION

FIG. 1 is a front perspective view of an alcohol sensing bracelet embodiment;

FIG. 2 is a front view thereof;
FIG. 3 is a rear view thereof with a door coupled into the bracelet;
FIG. 4 is a left view thereof;
FIG. 5 is a right view thereof;
FIG. 6 is top view;
FIG. 7 is a bottom view;
FIG. 8 is back perspective view with the door in an exploded position;
FIG. 9 is a front perspective view of another alcohol sensing bracelet embodiment;

FIG. 10 is a front view thereof;
FIG. 11 is a rear view thereof with a door coupled into the bracelet;
FIG. 12 is a left view thereof;
FIG. 13 is a right view thereof;
FIG. 14 is a top view thereof; and,
FIG. 15 is a bottom view thereof.
All broken lines represent unclaimed features of the article to which the design is applied. All surfaces not shown form no part of the claimed design.
